UNITED STATES PATENT OFFICE.

FRANCES K. SCHURMEIER, OF ST. PAUL, MINNESOTA.

EAR SHIELD OR PROTECTOR.

1,255,800.

Specification of Letters Patent. Patented Feb. 5, 1918.

Application filed May 19, 1917. Serial No. 169,613.

To all whom it may concern:

Be it known that I, FRANCES K. SCHURMEIER, a citizen of the United States, residing at St. Paul, in the county of Ramsey and 5 State of Minnesota, have invented certain new and useful Improvements in Ear Shields or Protectors, of which the following is a specification.

This invention relates to an ear shield or 10 protector designed for application to the human ear for the purpose of preventing the entrance of water thereto, the primary object of the invention being to provide a device of this character which may be worn 15 during the operation of shampooing the hair or by a bather to prevent the entrance of water to the ear, whereby liability of injury to the ear may be avoided.

A further object of the invention is to 20 provide a shield or protector of the character described which may be simply and economically made from a water proof substance, such as sheet rubber, and which may be applied and removed with ease and convenience.

With these and other objects in view, the invention consists of the features of construction, combination and arrangement of parts, hereinafter fully described and 30 claimed, reference being had to the accompanying drawing, in which:—

Figure 1 is an outer side view showing the mode of use of one of the shields.

Fig. 2 is an inner side or face view of the 35 shield removed.

Fig. 3 is a sectional view through the shield taken on the line 3—3 of Fig. 2.

Fig. 4 is a view similar to Fig. 2 showing a slight modification.

Fig. 5 is a plan view of the blank from 40 which the shield is made.

In carrying my invention into practice, I provide a shield 1 made of thin sheet or tissue rubber or some other suitable water 45 proof material. This shield is of a shape or conformation adapted to snugly fit and inclose the ear, as shown in Fig. 1, and capable, if desired, of being slightly expanded or distended and adapted to be applied to ears 50 varying to certain degrees in size, and to gently grip the ear by its contractile energy to assist in holding it in position.

The shield having these characteristics 55 comprises a sack of the general form defined composed of front and rear or outer and

inner walls 2 and 3, said walls being free from connection at the contracted portion of the sack to form a mouth or entrance passage 4, whereby it is adapted to be applied and removed. The outer or front wall 2 is 60 provided with a tapered portion 5 projecting beyond the line of the mouth to cover the front portion of the ear between and in the region of the tragus, while the rear wall 3 is provided along the region of the mouth 4 65 with a curved or segmental recess 6 to conform to the shape of the inner edge of the ear and fit snugly about the same. This recess 6 terminates short of the ends of the sack leaving tabs or projections 7 at the ends 70 of the recess which extend in front and rear of the ear and adapting the sack to be fitted fully down upon the same.

Projecting from the portion 4 of the wall 2 is a lobular extension 8 adapted to be extended downwardly beyond the tragus and over upon the cheek, to fully cover and protect the opening of the ear against the access of moisture and other foreign substances. For the purpose of securing this extension 8 80 in position, so that said extension will form with the portion 4 a water-shed, any suitable means may be provided to hold said extension in position upon the cheek. To this end the inner face of said extension may be provided with a securing coating 9 of rubber cement or other suitable water proof cement which will adhere to the cheek and thus secure the extension in position and hold the shield in place against any possibility of dislocation or displacement. In Fig. 4 I have shown a modified form of securing means consisting of a fastening strip 10 coated with rubber skin or other suitable adhesive material and which is adapted to serve the same 95 purpose as the cement coating 9.

In order to secure ease and economy of manufacture, as well as to enable the device to be conveniently formed into proper shape, I preferably make the shield from a single 100 piece of rubber or like sheet material, cut out initially in the form of a blank such as shown in Fig. 5. This blank is in general of substantially oval form, the end edges being cut inwardly on curved lines to form 105 recesses 11, while the body of the blank is formed with a curved slit 12 producing the curved marginal edge 6 of the wall 3 and the extension 8 of the wall 2, said slit extending at its ends to points inwardly of 110

and in line with the recesses 11, so as to produce the tabs 7 in the production of the complete article. The article is then formed or completed by folding the portions 2 and 3 of the blank along the medial portions formed by the parts 7, as indicated by the dotted lines in Fig. 5, so as to dispose the walls 2 and 3 in parallel relation, the outer marginal edges of said walls being then united by a line of stitching 13, or by other suitable means. When the portions 2 and 3 are thus folded over upon one another the opposed walls of the slit 12 will form the curved receding edge of the wall 3 and the extension 8 of the wall 2, as will be readily understood. By this mode of construction a shield of neat and attractive appearance, adapted to snugly and comfortably fit the ear, and which is water, dust and insect proof, may be conveniently and economically made.

The device is particularly adapted for use in beauty parlors, barber shops and like establishments, whereby the ears may be covered and protected against the access of water, particles of hair or other foreign substances during the operation of shampooing, hair cutting, and other like toilet manipulations, thus avoiding discomfort to the customer or patient as well as all troubles or diseases of the ear liable to be caused by the entrance of foreign substances. The shield may also be used by bathers to protect the ears from the entrance of water and obviate danger of injury to the ear drum.

Having described my invention, I claim:

1. An ear shield or protector for the purposes described, comprising a sack of water proof elastic tissue to inclose and cover the ear, and having a portion to extend beyond the lobule of the ear and over upon the cheek of the wearer, said portion being adapted for attachment to the cheek of the wearer.
2. An ear shield or protector comprising a sack of water proof material adapted to be fitted upon and inclose the ear, and having a portion adapted for attachment to the cheek of the wearer.
3. An ear shield or protector comprising a sack of elastic water proof material adapted to be fitted upon the ear to cover and in-

close the same, and provided with means of attachment to the cheek of the wearer.

4. An ear shield or protector comprising a sack of water proof material adapted to inclose and cover the ear, said sack being provided on its outer side with an extension to project beyond the opening of the ear and over upon the cheek of the wearer.

5. An ear shield or protector comprising a sack conforming in shape to the external ear and adapted to be fitted upon the same, said sack embodying an outer wall and an inner wall, the inner wall having a curved marginal portion to fit the inner ridge of the ear and the outer wall having an extension beyond said marginal portion to project beyond the opening of the ear over upon the cheek of the wearer.

6. An ear shield or protector comprising a sack of water proof material having a mouth or opening at one side and adapted to be fitted upon the ear to inclose and cover the same, said sack having an inner wall provided with a curved margin at one side of the mouth and an outer wall provided with a lobular extension beyond said mouth, said extension being provided with means for attachment to the cheek of the wearer.

7. An ear shield or protector comprising a sack-like body of elastic water proof material, said sack-like body having a mouth portion and embodying inner and outer walls, the outer wall having an extension beyond the mouth portion to cover the opening of the ear and to extend over upon the cheek of the wearer.

8. The herein described method of making an ear shield or protector of the character described, which consists in cutting out a blank from water proof sheet material, said blank being of approximately oval form and having inwardly extending end recesses and an arcuate slit formed at one side of the longitudinal center of the blank and having its terminals in line with said recesses, folding the blank centrally on a longitudinal line intersecting said recesses, and then uniting the marginal edges of the blank.

In testimony whereof I affix my signature.

FRANCES K. SCHURMEIER.
